UNITED STATES PATENT OFFICE.

ARMAND LEJEUNE, OF VERVIERS, BELGIUM.

DIVIDING APPARATUS FOR CARDING-ENGINES.

SPECIFICATION forming part of Letters Patent No. 616,946, dated January 3, 1899.

Application filed December 27, 1897. Serial No. 663,616. (No model.)

To all whom it may concern:

Be it known that I, ARMAND LEJEUNE, a subject of the King of Belgium, residing at Verviers, in the Kingdom of Belgium, have 5 invented certain new and useful Improvements in Dividing Apparatus, of which the following is a specification.

This invention has been patented in Belgium under date of March 3, 1897, No. 126,691, 10 and May 8, 1897, No. 128,125; in France under date of August 12, 1897, and in England under date of August 23, 1897, No. 19,428.

My invention relates to improvements in dividing apparatus for use in connection with 15 carding-engines and wherein straps are used for forming the fleece slivers or ribbons. Hitherto in such devices it has been customary to give the strap a half-turn in passing from the dividing-rollers to the guide-rollers in 20 order to bring them into a vertical plane at the front of crossing that portion of the strap carrying the fleece, and thus prevent their seizing the fleece. The result of giving the strap a half-turn is to cause it to run part of 25 the time with the smooth side out and the other time with the rough side out, and in order to insure the smooth side being always in contact with the fleece it has been customary to cut the belt and join the severed ends 30 again after having given one end a half-turn.

The object of the present invention is to cause the belt to run with the smooth side always in contact with the fleece and yet do away with having any permanent twist in the 35 belt.

My invention is illustrated on the annexed drawings, in which—

Figure 1 is a side view of the parts of the dividing apparatus or so-called "condenser." 40 Fig. 2 is a front view of the same parts as shown in Fig. 1. Fig. 3 is a side view of some modifications.

The guiding-rollers C C' for the straps L L' are provided between their flat usual grooves G with other grooves R, much deeper and smaller, into which the endless straps are brought to penetrate, thus being turned edge-wise before passing over the tension-rollers T T' and returning to the dividing-rollers. 45

Instead of making the deep grooves R R' in the guide-rollers C C' they can be formed in the dividing-rollers D D', as shown in Fig. 3.

Similar grooves may also be formed both in the dividing and in the guiding rollers.

The belt is passed over the dividing-rollers 55 and guide-rollers in such a manner that in passing, for instance, from guide-roller C to the guide roller T' it is given a quarter-turn between roller C and roller R and is turned back again an equal amount between the roller 60 C' and roller T', so that it passes around roller T' with its same side outward instead of the faces being reversed, as has been the case when a complete half-turn is given to the belt in passing between said pulleys. Owing to the 65 deep groove being of substantially the same width as the thickness of belt or only slightly in excess thereof the belt is always maintained on edge at the front of crossing the fleece, while its smooth side is always maintained 70 outward for contact with the fleece.

It has hitherto been the practice to impart a to-and-fro movement to the roller V, which serves to guide the fleece toward the sleeves in order to prevent its becoming clogged with 75 the fibers detached from the slivers. It has been found, however, that the desired result is not attained. I therefore provide under the said roller and in contact therewith a second roller w, which serves to clean it and 80 does not permit the fibers or the like collected to pass to the slivers or ribbons.

Having thus described my invention and how to carry it into practice, I declare that what I claim as my invention is— 85

In a condenser or fleece-dividing apparatus, the combination with the dividing-rollers D D', and guide-rollers C C', and T T', part of said rollers having narrow and deep grooves corresponding in width to the thickness of 90 the belt, of an endless belt passing around said rollers and being held edgewise by said narrow and deep grooves, said belt being given a quarter turn or twist on one side of the grooved roller and a reversed turn to an 95 equal degree on the opposite side, substantially as described.

In testimony whereof I have signed this specification in the presence of two subscribing witnesses.

ARMAND LEJEUNE.
